ଶର୍ମିତା

UNITED STATES PATENT OFFICE.

JESSE MATTERN, OF TYRONE, PENNSYLVANIA.

SHADE AND CURTAIN HANGER.

1,236,332.

Specification of Letters Patent.

Patented Aug. 7, 1917.

Application filed October 18, 1916. Serial No. 123,337.

To all whom it may concern:

Be it known that I, JESSE MATTERN, a citizen of the United States, residing at Tyrone, in the county of Blair and State of Pennsylvania, have invented certain new and useful Improvements in Shade and Curtain Hangers, of which the following is a specification, reference being had to the accompanying drawings.

10 This invention relates to certain improvements in shade and curtain hangers and it is an object of the invention to provide a device of this general character which may be conveniently and effectively applied in operative position and which may be readily adjusted to compensate for windows or shades of varying widths.

15 The invention consists in the details of construction and in the combination and arrangement of the several parts of my improved shade and curtain hanger whereby certain important advantages are attained and the device is rendered simpler, less expensive and otherwise more convenient 20 and advantageous for use, all as will be hereinafter more fully set forth.

25 The novel features of the invention will hereinafter be definitely claimed.

30 In order that my invention may be the better understood, I will now proceed to describe the same with reference to the accompanying drawings, wherein—

35 Figure 1 is a view in perspective of a shade and curtain hanger constructed in accordance with an embodiment of my invention; and

40 Fig. 2 is an enlarged vertical section taken through the device as herein embodied and illustrating certain parts of the device in elevation.

45 As herein embodied, my improved device comprises two sections A and B, said sections being substantially identical in construction except that the section A is provided with a guideway with which the section B coacts so that said sections A and B may be adjusted as the requirements of practice may require.

50 Each of the sections A and B comprises the elongated body member 1 having its outer end provided with the outturned wing 2 provided with means as indicated at 3 whereby the same may be engaged with a window shade, and is further provided with 55 the upstanding extension 4 adjacent the wing 2 terminating in the lateral extension

5 disposed longitudinally of the member 1 and in a direction away therefrom and being continued in a forwardly directed arm 6, whereby a curtain pole may be effectively supported thereby. The wing 2 also extends partly along the inner or connected end portion of the extension 4 to brace or reinforce the same.

60 Each of the sections A and B at a point inwardly of the extension 4 is provided with the upstanding arm 8 terminating in a rearwardly disposed hook 9 which is adapted to be engaged with the facing of a window casing whereby it will be perceived that my improved shade and curtain hanger may be conveniently and effectively applied and maintained in operative position.

65 It is preferred that the arm 8 be provided with the opening 10 through which a nail 75 or other fastening member may be disposed and engaged with the window frame in order to hold the section against longitudinal movement.

70 It is also to be observed that the wing 2 at the outer end of the section A or B extends below said section as is clearly illustrated in Figs. 1 and 2. By this arrangement lateral turning of the sections A and B under the influence of the weight imposed thereon 85 either by a shade or curtain is prevented.

75 From the foregoing description, it is thought to be obvious that a shade and curtain hanger constructed in accordance with my invention is of an extremely simple and 90 comparatively inexpensive nature and is particularly well adapted for use by reason of the convenience and facility with which it may be assembled, and it will also be obvious that my invention is susceptible of 95 some change and modification without material departure from the principles and spirit thereof and for this reason I do not wish to be understood as limiting myself to the precise arrangement and formation of 100 the several parts herein shown in carrying out my invention in practice, except as hereinafter claimed.

I claim:

105 A device of the character described consisting of two substantially duplicate sections, each of said sections comprising an elongated member adapted for telescopic engagement with the elongated member of the second section, the outer end of the member 110 being provided with an upstanding extension terminating in an outwardly directed

extension disposed longitudinally of the member, said second extension terminating in a forwardly directed arm substantially perpendicular to the second extension, said 5 forwardly directed arm serving as a support, the outer end of the section being provided with a forwardly directed wing extending partially along the first named extension and also extending below the elongated member, and an upstanding arm car-

ried by the elongated member at a predetermined point inwardly of the first named extension, said upstanding arm terminating in a rearwardly directed hook.

In testimony whereof I hereunto affix my 15 signature in the presence of two witnesses.

JESSE MATTERN.

Witnesses:

JOHN E. McGOVERN,
WILLIAM NELSON.
